WALL MOUNTED SHELF STRUCTURE

Louis E. Fulton, Houston, Tex.

Application May 21, 1949, Serial No. 94,760

3 Claims. (Cl. 312—245)

1

This invention relates to an improved form of shelf structure and particularly to a telephone supporting shelf attachable to a building wall or the like.

The principal objects of this invention are to provide a removable telephone shelf or support bracket which may be readily attached to a building wall at any convenient location; which eliminates the need for a permanent wall receptacle commonly required in most buildings, or of a special stand which occupies otherwise useful floor space; which is of relatively simple and low-cost construction; and which is attractive in appearance.

Other and more specific objects and advantages of this invention will become more readily apparent from the following detailed description when read in conjunction with the accompanying drawings which illustrate one useful embodiment in accordance with this invention.

In the drawings:

Fig. 1 is a view looking upwardly toward the bottom of a shelf structure in accordance with this invention, some of the parts being broken away for purposes of better illustration;

Fig. 2 is a longitudinal cross-sectional view taken along line 2—2 of Fig. 1;

Fig. 3 is a transverse cross-sectional view taken along line 3—3 of Fig. 2;

Fig. 4 is a front-end elevational view of the shelf structure; and

Fig. 5 is a sectional detail illustrating the relative positions of some of the parts occupied at one stage in mounting the structure on its support bracket.

Referring to the drawings, the shelf structure includes a horizontally disposed generally rectangular platform 10 supported on an angular bracing piece, indicated generally by the numeral 11. The latter is composed of a pair of vertically disposed flat side members 12—12, arranged in parallel and laterally spaced apart, and cross-connected by means of a face plate 13 connected between the lower edges of the side members and curved to conform with their generally angular configuration. Side members 12—12 and face plate 13 may be molded in the form of a unitary structure from conventional thermo-setting plastic material to form a hollow shell-like bracing piece, as illustrated, having the several edges and angles thereof smoothly rounded and curved to provide an attractive appearance, as illustrated. The bracing piece will thus have an inner vertically extending edge 14 adapted to fit snugly against a supporting wall W, to which the struc-

ture is to be attached, and an upper generally horizontal edge 15 on which platform 10 is supported. The latter is made somewhat wider than bracing piece 11 so that when suitably centered thereon, the side edges of the platform overhang the opposite sides of the bracing piece. A pair of flanges 16—16 depend from the side edges of platform 10 parallel to and spaced outwardly from side members 12—12. A second pair of flanges 17—17 depend from the lower face of platform 10 and are inwardly spaced from and parallel to flanges 16—16. Flanges 17—17 are positioned on the lower face of platform 10 to be in registration with the horizontal upper edges of side members 12—12 and are adapted to be suitably connected thereto as by gluing or by any other suitable fastening means. The spaces between adjacent flanges 16 and 17 form guide channels 18—18, the forward ends of which are closed by end pieces 19—19 extending between the forward ends of the adjacent flanges 16 and 17. The inner ends of channels 17—17 are open, flanges 17 being made slightly shorter than flanges 16 which extend to the rearward end of platform 10 and are made substantially flush with this end of the latter and with vertical edge 14 of the bracing piece. Extending inwardly from the inner ends of flanges 16 and generally parallel to the inner end of platform 10 are a pair of depending stop members 20—20 which extend partly across the respective channels 18—18. The upper face of platform 10 is provided with an upwardly extended rim 21 which extends along the side edges and across the forward end thereof to provide an enclosed area of the same general shape as platform 10 to receive a telephone base or other object which it may be desired to place thereon. Rim 21 thus serves as a guard to prevent the object from sliding off the platform. Platform 10, including flanges 16 and 17, end pieces 19, and rim 21, is preferably constructed of thermosetting plastic, generally identical to that from which bracing piece 11 is constructed, and is molded into a one-piece unitary structure, forming a sub-assembly which can be connected to bracing piece 11 by joining flanges 17 to the upper horizontal edges of side members 12—12, as previously mentioned. The space between flanges 17—17 and beneath platform 10 is designed to form a generally rectangular receptacle 22 adapted to receive a correspondingly shaped drawer 23 which is insertable through the forward end of receptacle 22 and is slideable inwardly and outwardly therefrom. The upper horizontal edges of side members 12—12 are laterally inwardly thickened, as at 24—24 to form

rails on which drawer 23 is supported in its sliding movement. A depending stop member 25 extends from beneath platform 10 between the inner ends of flanges 17 to form an inner stop for drawer 23.

A generally U-shaped bracket, indicated generally by the numeral 26, constructed of flat strip metal, has parallel arm members 27-27 connected by a base piece 28. Bracket 26 is adapted to be connected to wall W by means of screws 29 or other suitable fastening means, which extend through suitable holes in base piece 28 into the wall. The corners formed by the juncture of arm members 27 with base piece 28 are inwardly indented to form recesses 30-30 for reception of stop members 20-20, as will be described hereinafter. The medial portions of the end of platform 10 and the lower end of bracing piece 11 are provided with vertically aligned notches 31 and 32, respectively, in which a wire, such as a telephone cord, may be enclosed when the structure is placed against wall W.

To mount the structure on wall W, bracket 26 is fastened thereto by driving screws 29 through base piece 28, arms 27 thus being caused to extend outwardly from wall W. The shelf structure, in fully assembled form, will then be installed on bracket 26 by inserting the extended ends of arms 27 into the open inner ends of guide channels 18. In this stage of mounting the shelf structure will be slightly elevated relative to arms 27, so that stops 20 will be slightly above the upper edges of arms 27, as illustrated in Fig. 5. It will be understood that the vertical dimension of arms 27 will be less than the vertical dimension of channels 18 to permit elevation of the shelf structure relative to arms 27 sufficient for accomplishing this operation. In this position, the shelf structure will be moved inwardly along arms 27 until the inner end of the structure comes up against wall W and stops 20 are in vertical registration with recesses 30. Thereupon the shelf structure will be allowed to drop down sufficiently to cause stops 20 to enter recesses 30, thereby locking the shelf structure to the bracket. The platform will now rest firmly on the upper edge of bracket 26 and will be locked against forward movement relative thereto, while bracing piece 11 will be in firm contact with the face of wall W and by its angular construction and connection to platform 10, will serve to effectively brace the latter for the support of any object which may be placed thereon.

To remove the shelf structure, it is only necessary to again raise the shelf structure relative to bracket 26 to allow stops 20 to clear recesses 30. The structure may then be drawn forwardly off of arms 27. Bracket 26 may now be removed from the wall and transferred to another location whereupon the shelf structure may be again installed thereon in the manner described.

It will be seen that in accordance with this invention a shelf structure is provided which is highly utilitarian, attractive in appearance, which is readily movable from place to place and may be installed at any convenient location in a residence or office. While designed particularly for use as a telephone stand, it will, of course, serve to support other objects from a room wall.

It will be understood that various modifications and changes may be made in the details of the illustrative embodiment within the spirit of this invention but without departing from the scope of the appended claims.

What I claim and desire to secure by Letters Patent is:

1. A shelf structure of the class described, comprising, a platform portion, an angular bracing piece for bracing the platform from a supporting wall, a pair of laterally spaced channels formed beneath said platform portion and extending longitudinally adjacent each side thereof and opening to the rear of said platform portion, a pair of stop members depending from the rearward end of said platform portion into said channels, and a generally U-shaped bracket having its arms spaced for insertion into said channels and its base portion attachable to said supporting wall, said arms having inwardly extending recesses therein for reception of said stop members to lock said structure to said bracket.

2. A shelf structure of the class described, comprising, a platform portion, an angular bracing piece for bracing said platform portion from a supporting wall, pairs of spaced parallel flanges depending from said platform portion and extending longitudinally along each side thereof to form a pair of longitudinal channels opening to the rear of said platform portion, a pair of stop members depending from the rearward end of said platform portion into said channels, and a generally U-shaped bracket having its arms spaced for insertion into said channels and its base portion attachable to said supporting wall, said arms having inwardly extending recesses therein for reception of said stop members to lock said structure to said bracket.

3. A shelf structure of the class described, comprising, a platform portion, an angular bracing piece for bracing said platform portion from a supporting wall, pairs of spaced parallel flanges depending from said platform portion and extending longitudinally along each side thereof to form a pair of longitudinal channels opening to the rear of said platform portion, said pairs of flanges being spaced apart to form a receptacle opening forwardly beneath said platform portion, a pair of stop members depending from the rearward end of said platform portion into said channels, a generally U-shaped bracket having its arms spaced for insertion into said channels and its base portion attachable to said supporting wall, said arms having inwardly extending recesses therein for reception of said stop members to lock said structure to said bracket, and a drawer slidably disposed in said receptacle for slidable movement inwardly and outwardly thereof.
